United States Patent

Des. 240,083

Patented May 25, 1976

240,083

URINAL

Heinz H. W. Gregor, Toronto, Ontario, Canada
(2438 Bloor St. W., Islington, Ontario M6S 1P9, Canada)

Filed Oct. 1, 1973, Ser. No. 402,084

Term of patent 14 years

Int. Cl. D24—04

U.S. Cl. D83—1 U

FIG. 1

FIG. 2

FIG. 3

FIG. 4

FIG. 5

FIG. 6

FIG. 1 is a perspective view of a urinal showing my new design;

FIG. 2 is a perspective view taken from a point opposite that shown in FIG. 1;

FIG. 3 is a side elevational view;

FIG. 4 is a front elevational view;

FIG. 5 is a rear elevational view; and

FIG. 6 is an exploded bottom perspective view thereof on an enlarged scale.

I claim:

The ornamental design for a urinal, as shown.
